UNITED STATES PATENT OFFICE.

JEHYLEMAN SHAW, OF BRIDGEPORT, CONNECTICUT.

IMPROVED APPARATUS FOR SAVING SILVER FROM WASTE SOLUTIONS.

Specification forming part of Letters Patent No. 35,842, dated July 8, 1862.

To all whom it may concern:

Be it known that I, JEHYLEMAN SHAW, of the city of Bridgeport, in the county of Fairfield and State of Connecticut, have invented a new and improved mode of preventing the gold and silver contained in solutions used in photographic and other establishments from running to waste and being lost; and I do hereby declare that the following is a full and exact description thereof, reference being had to the accompanying drawings, and to the letters of reference marked thereon.

The nature of my invention consists in placing under the waste-pipe of the sink or basin, over which solutions of silver or gold are used, a vessel to receive the material escaping from the sink, which vessel is provided with such chemicals as will cause the silver or gold contained in the liquids falling into it to be precipitated, while the surplus water and other worthless material are allowed to escape through a waste-pipe, after first passing through a filter or strainer.

For a more full description of my invention, I would refer to the accompanying drawings.

Figure 1 represents my machine and the interior arrangements thereof, the outside being drawn as though it were made of glass. A represents the outside case of the machine, which may be made of wood or metal, open at the top, and closed at the bottom. F represents the waste-pipe of the sink, through which the liquids from the sink pass into the machine. E represents a partition of wood or metal, extending entirely across the case and fitted to the sides thereof water-tight, and also extending from the top of the case to within about an inch of the bottom. D is a cloth bag containing two or three pounds of protosulphate of iron. This bag is suspended from the top of the case by the string G, so as to be about midway between the top and bottom of the case. B represents a filter, with a waste-pipe, C, extending from the inside of the filter to the outside of the case.

Fig. 2 is a vertical section of the filter through the center. The filter is made of a wood or other box open at the bottom, but inclosed on all other sides. Near the top of the box the waste-pipe C is inserted. Immediately underneath the waste-pipe a cloth

strainer is stretched across the box and secured thereto. This strainer is represented by the line i. Immediately under the strainer is a layer of cotton-batting is placed, which is represented by k. The space marked L is entirely filled up with sawdust. Another layer of cotton-batting is placed next the sawdust, as represented by M, and another cloth strainer, N, is then stretched across the bottom of the box and secured thereto. H is an open space between the upper strainer and the top of the box.

The machine, as thus described, is ready for use, and is placed under the waste-pipe of the sink or basin, into which solutions containing silver or gold are wasted, and in such a position that the waste from the sink shall fall into that portion of the vessel in which the bag D is suspended. As the liquids containing solutions of gold or silver run into the vessel A, and come into contact with the bag containing protosulphate of iron, a chemical action takes place, and the silver contained in solution is precipitated. As the vessel fills the surplus water and other worthless liquids pass through the filter and out at the waste-pipe C, the filter preventing small particles of silver from being drawn by the current out of the waste-pipe.

The machine may be made of any size, from one foot in diameter and upward, and of any desired height according to the quantity of waste from the sink. The vessel can be relieved of the silver which has been precipitated at any time, and the silver refined, when desired. There are many other chemicals which may be used in the bag, instead of the protosulphate of iron. If desired, metals may be used. The filter may also be made in a variety of ways and shapes, but the one adopted is sufficient to answer the purpose. Indeed, the machine will answer a very good purpose without any filter. It will be necessary from time to time to replenish the bag D as the chemicals therein contained will be gradually dissolved.

Having thus described my invention, what I claim therein as new, and desire to secure by Letters Patent, is—

1. Attaching to the waste-pipe of the sink or basin, into which persons using silver in solutions suffer them to be wasted, a vessel so

arranged and constructed that the liquids passing from the sink shall run into, through, and out of said vessel, and between the time of entering said vessel, and escaping therefrom shall be brought into contact with such chemicals or metals as will cause the whole or any part of the silver contained in solution to be precipitated and retained in said vessel, while the worthless material is allowed to escape.

2. The use of the filter B or its equivalent, for the purpose of preventing small particles of silver from escaping after the liquids have been brought into contact with the chemicals as described.

JEHYLEMAN SHAW.
